UNITED STATES PATENT OFFICE.

CHARLES C. BONNERT, OF BALTIMORE, MARYLAND.

DESIGN FOR A BOTTLE.

SPECIFICATION forming part of Design No. 36,262, dated March 31, 1903.

Application filed February 21, 1903. Serial No. 144,532. Term of patent 3½ years.

To all whom it may concern:

Be it known that I, CHARLES C. BONNERT, a citizen of the United States, residing at Baltimore, in the State of Maryland, have invented and produced a new, original, and ornamental Design for Bottles, of which the following is a specification.

This invention relates to a new, original, and ornamental design for bottles.

10 The leading or material features of my design consist of a bottle having a circular-shaped body provided with a neck and a base and a central depression, the portion of the body between the outer circumference of the 15 central depression and the outer edge of the bottle-body being convex in cross-section and provided with four slightly-raised serrated surfaces arranged equidistant upon the said convexed surface of the body, two of said serrated surfaces being provided with raised stars and a rope extending around the said convexed surface and projecting under each of the said serrated surfaces, all arranged to represent a life-preserved or life-buoy and to 25 give an ornamental appearance.

In the drawings, Figure 1 is a front elevation of a bottle, showing my design; and Fig. 2 is a section on the line X X of Fig. 1.

Referring to the accompanying drawings,

1 designates the body of the bottle, having a 30 neck 2 and a flat base 3, upon which the bottle rests. The body of the bottle is provided with a central depression 4 and a convexed portion 5, extending from the central depression to the outer edge, the said convexed portion 5 being provided with four slightly-raised serrated surfaces 6, which extend from the central depression 4 to the outer edge of the body, two of said surfaces 6 being provided with stars 7, which latter are raised above 40 said surfaces. Extending around the body of the bottle, near the outer edge thereof, in an irregular line is a rope 8, projecting under the surfaces 6, all of the said parts being so arranged as to represent a life-preserved 45 or life-buoy and to give an ornamental appearance to the bottle.

Having thus described my invention, what I claim is—

The ornamental design for a bottle as herein shown and described. 50

In testimony whereof I affix my signature in the presence of two witnesses.

CHARLES C. BONNERT.
